UNITED STATES PATENT OFFICE.

WALTER L. CAVEN, OF CINCINNATI, OHIO, ASSIGNOR OF ONE-FOURTH TO WALTER MACLEOD, OF CINCINNATI, OHIO.

RAILWAY-RAIL.

992,162.

Specification of Letters Patent. Patented May 16, 1911.

Application filed August 8, 1910. Serial No. 576,061.

To all whom it may concern:

Be it known that I, WALTER L. CAVEN, a citizen of the United States of America, and resident of Cincinnati, county of Hamilton, State of Ohio, have invented certain new and useful Improvements in Railway-Rails, of which the following is a specification.

The object of my invention is a railway rail, of a form which offers a maximum resistance to the bending strains to which such rails are subject. This object is attained by the means described in the specification, and illustrated in the accompanying drawings, in which,

Figure 1 is a perspective view of a railway track equipped with a rail embodying my invention. Fig. 2 is a side elevation of a section of track, and of a rail embodying my invention, upon an enlarged scale, one-half only of the rail joint being shown. Fig. 3 is a sectional view taken upon line 3—3 of Fig. 2. Fig. 4 is a sectional view taken upon line 4—4 of Fig. 2.

Referring to the parts:—The tread, A, and the web, B, of the rail are of ordinary construction. At points which register with the usual ties, D, the portion, e, of the base, is of the usual flat construction. Intermediate the rails, the two flanges, e¹, e², of the base, are bent downward in a manner such that at points midway between the ties, the flanges lie in substantially vertical planes, as illustrated in Fig. 3. Adjacent to the ties, the bends, e³, e⁴, of the flanges are in planes inclined to the vertical, so that the base portion is bent gradually from its horizontal position over the ties, to a substantially vertical position, at points intermediate the ties. At the ends of the rails, the flanges of the base terminate in portions which stand in vertical planes.

In conjunction with my rails, I employ a rail-joint, which has a central body portion, which consists of plates, F, F', which contact with the downturned flanges of the base and extend upwardly in parallelism with the web of the rail, and have their upper edges in contact with the underside of the tread. Upon each side of the central body portion, the plate has arms, f, f', which stand adjacent to the webs of the rail over the ties. The plates, F, F', are joined at the center by plate F². Plates, F, F', the central portion F² and the arms, f, f', are formed integral. Plates, F, F', and the

downturned flanges of the rail are perforated to pass bolts, G, G', and the plates, F, F', and the arms, f, f', have perforations registering with perforations in the webs of the rails, to receive bolts, G³, G⁴.

In use:—The rails having been formed with the flat portions of the base of the rails spaced at distances apart equal to the distances between the ties, the rails are placed upon the ties, with the downturned flanges occurring between the ties, and with the rails meeting each other at points between the ties. A rail-joint is secured in place, by sliding it over the end of a rail which has been secured in place, and then by sliding the next rail which is to be installed, into the end of the rail-joint, and bringing it into contact with the end of the rail just fixed in place. When a train passes over the rails, it subjects them to strains which tend to deflect them. These strains are greatest at points intermediate the ties. The downturned flanges being in vertical planes at the points intermediate the ties, are in a position in which they offer the maximum resistance to bending strains. The tractive force of a train moving over a rail, tends to make the rail move in relation to the ties. The downturned flanges of the rail base resist this tendency of the rail to move in relation to its ties.

What I claim is:—

1. A railway rail comprising a tread, a web and a base distorted at intervals along its length for stiffening the rail.

2. A railway rail comprising a tread, a web and bottom flanges distorted at intervals along their length for stiffening the rail.

3. A railway rail having its base bent out of a horizontal plane at points between the ties, and having horizontal portions in the base adapted to rest upon the ties.

4. A railway rail having its base downturned at points between the ties, and having flat portions adapted to rest upon the ties.

5. The combination of railway rails having their bases downturned at their ends, rail-joints bent around the abutting downturned bases of the rails, and means for securing the rails and rail-joints together.

6. The combination of railway rails having the bases downturned at the end of the rails, rail-joints having a central portion

passing beneath the downturned ends of the bases and bent upward on each side of the rails, and having longitudinally extending arms to contact with the webs of the rails, 5 said rail-joints and the flanges and webs of the rails being perforated, and bolts passing through the perforations to secure the rails and rail-joints together.

7. A railway rail comprising a tread, a web and bottom flanges located on each side 10 of said web and bent downwardly between the ties for the purpose of stiffening the rail.

WALTER L. CAVEN.
